UNITED STATES PATENT OFFICE.

FRIEDERICH WILLIAM BECKER, OF NEW ATHENS, ILLINOIS.

RAILWAY-CAR-STEP EXTENSION.

1,248,245.

Specification of Letters Patent. Patented Nov. 27, 1917.

Application filed July 9, 1917. Serial No. 179,522.

To all whom it may concern:

Be it known that I, FRIEDERICH W. BECKER, a citizen of the United States, residing at New Athens, in the county of St.

5 Clair and State of Illinois, have invented certain new and useful Improvements in Railway-Car-Step Extensions; and I do declare the following to be a full, clear, and exact description of the invention, such as 10 will enable others skilled in the art to which it appertains to make and use the same.

My invention has for its object to provide a simply constructed and inexpensive, yet a highly efficient and durable auxiliary step 15 for attachment to the lower steps of railway cars to assist the passengers in entering and leaving the same, thus obviating the use of the usual stools now commonly employed for this purpose.

20 With the foregoing general object in view, the invention resides in the novel features of construction and unique combinations of parts to be hereinafter fully described and claimed, the descriptive matter being supplemented by the accompanying drawings 25 which form a part of this specification and in which:

Figure 1 is a side elevation of a portion of a railway car showing the application of 30 my invention thereto; the auxiliary step being lowered;

Fig. 2 is a vertical transverse section on the plane indicated by the line 2-2 of Fig. 1;

35 Fig. 3 is a similar view showing the step raised; and

Fig. 4 is a perspective view illustrating one end of the frame which carries the auxiliary step.

40 In the drawings above briefly described, the numerals 1 designate a pair of horizontal bars adapted to extend transversely across the upper side of the lowermost step of the car, the rear ends of said bars being 45 bent downwardly and forwardly to provide hooks 2 which receive the rear edge of the step therein. Hinged at 3 to the front ends of the bars 1, are two vertically disposed bars 4 whose lower portions are bent forwardly to provide horizontal arms 5 which support thereon the auxiliary step 6, the front ends of said arms 5 being by preference bent upwardly at 7 into engagement with the outer edge of said step. The vertical bars 4 are rigidly connected by a horizontal bar 8 and the arms 5 are similarly

connected by a longitudinal bar 9, the ends of said bar 9 extending beyond the arms and being bent upwardly to form an ear 10 at each end 60

Rods 11 are pivoted at their lower ends to the ears 10 and at their upper ends are provided with eyes 12 adapted for passage over studs or knobs 13 carried by the sides of the car step, so that the auxiliary step may be 65 held in either raised or lowered position. Although any suitable type of handle could well be employed for operating the rods 11, the upper portions thereof are preferably bowed inwardly as indicated at 11^a, for this 70 purpose. This construction is simple and inexpensive, yet meets the requirement and is therefore preferred.

A pair of brackets 14 are rigidly secured to the vertical bars 5 and are adapted to 75 underlie the lower step of the car when the auxiliary step is lowered, said brackets thus serving to limit the downward movement of the auxiliary step and to effectively brace the same against sagging. The brackets 14 80 are by preference of substantially the shape of an inverted L, but any other required formation may well be employed, it being desirable, however, that each bracket be provided with a flat upper portion 14^a for 85 contact with the lower side of the step.

Preferably employed in connection with the features of construction above described, are two triangular end plates 16, said plates 90 contacting with the outer edges of the bars 4 and arms 5 and having their edges bent inwardly to form flanges 17 which are riveted or otherwise secured to said bars and arms. By this means, the arms 5 are prevented from springing downwardly and 95 added rigidity is therefore imparted to the entire device.

Normally, that is when the car is in motion, the auxiliary step 6 is raised and held in this position by engaging the eyes 12 100 with the uppermost studs or knobs 13. When, however, the car is stopped and passengers are to be loaded or unloaded, the eyes 12 are released so that the auxiliary step may be lowered by swinging it downwardly around the hinges 3. This having been done the rods 11 are properly engaged with the lower knobs 13 and then serve as additional means for bracing the entire step. 105

110 From the foregoing, taken in connection with the accompanying drawings, it will be

obvious that although the invention is of comparatively simple and inexpensive construction, it will be highly efficient and durable. Since probably the best results 5 are obtained from the specific features of construction shown and described, such features constitute the preferred form of the device. It is to be understood, however, that within the scope of the invention as 10 claimed, numerous minor changes could well be made.

I claim:

1. A car step extension comprising an auxiliary step, a frame by which said step is carried, said frame including a pair of end members each having a vertical bar, a pair of horizontal bars to which said vertical bars are hinged, said horizontal bars being adapted to overlie the lower step of 15 the car, and a pair of rigid brackets secured to said vertical bars and extending rearwardly to underlie said lower step when said auxiliary step is lowered.
2. A car step extension comprising a 20 pair of horizontal bars adapted to extend transversely across the lower step of the 25 car.

Copies of this patent may be obtained for five cents each, by addressing the "Commissioner of Patents, Washington, D. C."

car, the rear ends of said bars being bent downwardly and forwardly to form hooks for engagement with the rear edge of said step, a pair of vertical bars hinged to the 30 front end of said transverse bars and having their lower ends bent forwardly to provide horizontal arms, an auxiliary step supported upon said arms, horizontal bars extending between and connecting said vertical bars and said arms, a pair of end plates contacting with the outer edges of said vertical bars and arms and having their edges bent inwardly and secured thereto, and a pair of brackets rigidly secured to 40 and extending rearwardly from said vertical bars, said brackets being adapted to underlie said lower step when said auxiliary step is lowered.

In testimony whereof I have hereunto set 45 my hand in the presence of two subscribing witnesses.

FRIEDERICH WILLIAM BECKER.
